United States Patent Office

Des. 174,495
Patented Apr. 19, 1955

174,495

APRON

Edward E. Fraser and Betty J. Fraser, Conway, Ark.
Application September 29, 1953, Serial No. 27,004

Term of patent 3½ years

(Cl. D3—26)

To all whom it may concern:

Be it known that we, Edward E. Fraser and Betty J. Fraser, both citizens of the United States, both residing at Conway, in the county of Faulkner and State of Arkansas, have invented a new, original, and ornamental Design for an Apron, of which the following is a specification, reference being had to the accompanying drawing, forming a part thereof.

Figure 1 is a front perspective view of an apron embodying our design,

Figure 2 is a rear perspective view of the same,

Figure 3 is an enlarged central vertical longitudinal section through the apron,

Figure 4 is an enlarged horizontal transverse cross section taken substantially on line 4-4 of Figure 3, and

Figure 5 is a similar section taken substantially on line 5-5 of Figure 3.

We claim:

The ornamental design for an apron, substantially as shown.
